JOHN V. MOORE, OF PAWTUCKET, RHODE ISLAND, ASSIGNOR TO MOORE FABRIC COMPANY, OF PAWTUCKET, RHODE ISLAND, A CORPORATION OF RHODE ISLAND

CURVILINEAR ELASTIC FABRIC

Application filed September 21, 1928. Serial No. 307,424.

This invention relates to the production of a narrow elastic fabric having an inherent curvilinear shape, such a fabric being of great utility for many purposes.

5 It is the object of my invention to provide an elastic fabric of relatively narrow width in which the curvilinear form is developed in the weaving operation and is preserved throughout the finishing operation.

10 A further object is to provide a curvilinear elastic fabric in which the fabric is of substantially uniform weight and thickness in each unit area thereof.

I have also provided an improved method 15 of producing such a curvilinear elastic fabric, the several features of which will be herein-after described.

20 My invention further relates to arrangements and combinations of parts which will be hereinafter described and more particularly pointed out in the appended claims.

A preferred form of the invention, and mechanism adapted to the production thereof, are shown in the drawings in which 25 Fig. 1 is a perspective view of parts of a narrow ware loom on which my improved fabric may be produced;

Fig. 2 is a front view of one of the tapered warp beams;

30 Fig. 3 is a plan view of a portion of the fabric;

Fig. 4 is a diagrammatic sectional view, taken along the line 4-4 in Fig. 3;

35 Fig. 5 is an enlarged detail sectional view of a portion of the fabric; and

Fig. 6 is a diagrammatic plan view, illustrating the distribution of the warp and weft threads.

40 Referring to the drawings, my improved curvilinear fabric is preferably formed of a plurality of elastic warp threads 10, non-elastic warp threads 11, and non-elastic filling threads 12. The elastic warp threads 10 45 may be either plain rubber threads or may be covered rubber threads, depending upon the type of fabric to be produced.

The filling threads 12 extend from selvage to selvage of the fabric and assume a more or less fan-like relation, as they are neces-

sarily more widely spaced on the longer or outer curved edge of the fabric.

The warp threads 10 and 11 extend continuously longitudinally of the fabric and are preferably spaced more closely together 55 toward the outer or longer edge of the fabric, as indicated in Figs. 3, 4 and 6.

The principal object of gradually increasing the number of warp threads in this manner is to compensate for the separation of 60 the weft threads toward the outer edge of the fabric, thus providing a substantially uniform amount of combined warp and weft threads in each unit area of the fabric, the warp threads increasing in number as the 65 weft threads are more widely spaced.

While the warp threads 10 preferably vary in spacing as above described, they are preferably of uniform size or diameter from edge to edge of the fabric, as clearly shown in 70 Fig. 4.

My improved fabric may be made in a great variety of weaves, but a preferred form thereof is illustrated in Fig. 5, in which an elastic warp 10 and a pair of non-elastic 75 warps 11 are inserted between adjacent dents 15 of the reed 16 (Fig. 1), while the next adjacent reed spaces are preferably left empty. The effect of this arrangement is to crowd the non-elastic warps 11 closely against the 80 elastic warp 10, thus holding the elastic warp firmly in a tube-like pocket, so that the fabric may be cut into sections without undue shrinkage of the elastic warps after cutting.

With the construction shown, it is found that the lateral expansion of the elastic warp when released by cutting causes it to tightly fill the narrow pocket or tube between the adjacent non-elastic warps, so that it is immediately held from further shrinkage. 85

In the production of a curvilinear elastic fabric, it is essential that the warp threads be under substantially uniform tension throughout the width of the fabric. In order to attain this result, I provide a tapered warp beam 20 (Fig. 1) for the elastic warps 10 and a similarly tapered warp beam 21 for the non-elastic warps 11. The taper of the warp beam barrels is selected to give the increased length of warp required for the 100

longer edge of the fabric without increasing the tension thereon. The warps 10 and 11 are drawn along guide-rolls 22 (Fig. 1) and are threaded through two or more harnesses 24 and through the reed 16 previously described, the reed being mounted upon a lay 25.

The woven fabric passes around a tapered guide-roll 26 on the breast beam and around a tapered take-up roll 30, against which the fabric is held by a loose guide-roll 31. The fabric is then wound on a tapered cloth roll 32.

It will be seen that the curvilinear shape of the fabric is produced naturally by varying the length of the warp threads from edge to edge of the fabric, and that these warp threads are at all times held under substantially uniform tension. The provision of the separate warp beams 20 and 21 permits me to increase or decrease the tension on the elastic warp threads 10 as desired, independent of the tension on the non-elastic warp threads 11. It will be understood that the warp threads 10 are stretched substantially to their fullest extent during the weaving operation, so that the fabric may be rendered highly elastic by the subsequent shrinkage thereof.

It is essential that the curvilinear shape of the fabric be preserved throughout the sizing and finishing of the fabric and special mechanism has been provided for sizing and drying the fabric without disturbing or distorting its inherent curvilinear shape. The details of this mechanism, however, form no part of the present invention and are not claimed herein.

Having described the construction and method of production of my improved fabric, it will be seen that the fabric is produced in an inherent curvilinear shape, with the warp threads under substantially uniform tension throughout the width of the fabric. The curvilinear shape of the fabric does not depend on distortion of the fabric after weaving but is the inherent shape assumed during the weaving process. A fabric thus produced will naturally preserve its original curvilinear shape much better than a fabric in which the curve is produced by distortion or manipulation after the fabric is woven.

Having thus described my invention and the advantages thereof, I do not wish to be limited to the details herein disclosed, otherwise than as set forth in the claims, but what I claim is:

1. A woven fabric which is elastic longitudinally and substantially non-elastic transversely and which includes a plurality of rubber warp threads, said fabric being inherently curvilinear to a predetermined radius, and the rubber warp threads thereof being of substantially uniform diameter and being woven under substantially uniform tension throughout the width of the fabric.

2. A woven fabric which is elastic longitudinally and substantially non-elastic transversely, said fabric including rubber and non-elastic warp threads and being inherently curvilinear to a predetermined radius and the fabric being of substantially uniform weight and thickness per unit area from selavage to selavage thereof.

3. A woven fabric which is elastic longitudinally and substantially non-elastic transversely and which includes rubber and non-elastic warp threads, said fabric being inherently curvilinear to a predetermined radius and inherently elastic and having said rubber warp threads bound firmly between said non-elastic warp threads, all of said warp threads increasing uniformly in length from selavage to selavage of said fabric and being under substantially uniform tension in the finished fabric.

4. A woven fabric which is elastic longitudinally and substantially non-elastic transversely, and which includes rubber and non-elastic warp threads, said fabric being inherently curvilinear and having pairs of non-elastic warps closely adjacent each rubber warp with said latter warp therebetween, thereby to bind said rubber warp threads firmly between said non-elastic warp threads, the groups of warp threads each comprising a pair of non-elastic warps and a rubber warp being substantially spaced from each other.

5. The method of weaving a curvilinear elastic fabric which consists in supplying a plurality of both rubber and non-elastic warps, each kind of warp being distributed throughout the width of the fabric, in providing all of the rubber warps of substantially uniform diameter, in placing all of the rubber warps under a substantially uniform tension at the point of weaving, and in weaving said warp threads into an inherently curvilinear elastic fabric while said rubber warp threads are thus held under substantially uniform tension.

6. The method of weaving a curvilinear elastic fabric which consists in supplying a plurality of both rubber and non-elastic warps, each kind of warp being distributed throughout the width of the fabric, in providing all of the rubber warps of substantially uniform diameter, in placing all of the rubber warps under a substantially uniform tension at the point of weaving, and in delivering all of said warps to the weaving point at rates of feed varying uniformly from edge to edge of the fabric, whereby an inherent curvilinear set is produced in said elastic fabric.

7. The method of weaving a curvilinear elastic fabric which consists in supplying a plurality of both rubber and non-elastic warps, each kind of warp being distributed throughout the width of the fabric and said rubber warps being of substantially uniform

diameter, in inserting a rubber warp and a pair of non-elastic warps between adjacent dents of a reed, thereby to crowd the two non-elastic warps closely against the single rubber warp to hold said rubber warp firmly, in placing all of the warps of each kind under a substantially uniform tension, and in delivering said warps to the weaving point at rates of feed varying uniformly from edge to edge of the fabric whereby an inherent curvilinear set is produced in said elastic fabric.

8. The method of weaving a curvilinear elastic fabric which consists in supplying a plurality of both rubber and non-elastic warps, each kind of warp being distributed throughout the width of the fabric, in inserting a rubber warp and a pair of non-elastic warps between adjacent dents of a reed while leaving the next adjacent reed spaces empty, thereby to crowd the two non-elastic warps closely against the single rubber warp to hold said rubber warp firmly, in placing all of the rubber warps under a substantially uniform tension, and in delivering all of said warps to the weaving point at rates of feed varying uniformly from edge to edge of the fabric whereby an inherent curvilinear set is produced in said elastic fabric.

In testimony whereof I have hereunto affixed my signature.

JOHN V. MOORE.
